(57) **CLAIM**

I claim the ornamental design for a combination lighter and cutter, as shown and described.

DESCRIPTION

FIG. 1 is a perspective view of a combination lighter and cutter showing my new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a rear elevational view thereof;

FIG. 7 is a front elevational view thereof;

FIG. 8 is a perspective view thereof with the cover in its opened position; and,

FIG. 9 is a fragmentary perspective view showing the cutter in its operative position.

The portion shown in broken lines in FIG. 8 is included for illustrative purposes only and forms no part of the claimed design.
